ARVID H. NERO, OF NEW BRITAIN, CONNECTICUT, ASSIGNOR TO THE ARROW ELECTRIC COMPANY, OF HARTFORD, CONNECTICUT, A CORPORATION OF CONNECTICUT.

ELECTRIC SWITCH.

Application filed January 30, 1928. Serial No. 532,789.

My invention relates to electric switches, and particularly to switches for controlling lighting systems and light electrical equipment. It will be readily recognized that the 5 switch may be constructed for handling currents of large capacity, if so desired. Various features of improvement are herein-after described and shown in the accompanying drawings, in which

10 Fig. 1 is a plan view of a surface switch in which my invention is embodied in one form;

Fig. 2 is a section on the line 2—2, Fig. 1;

15 Fig. 3 is a side elevation of the switch mechanism and supporting frame attached;

Fig. 4 is a broken section on the line 4—4, Fig. 3; and

Fig. 5 is a plan of the blank from which the switch frame is formed.

20 While certain features of the present improvements may be applied to switches of other types, I have illustrated the invention in a surface toggle switch, to which certain features of construction are particularly applicable.

25 As indicated, the switch comprises a circular insulating base 6 recessed on its upper face to afford a central depressed area 7 on which the switch mechanism is supported. A peripheral ledge 8 affords a seat 30 for the switch cover 9 and its insulating lining 10, while the up-standing plateaus 11 on opposite sides of the depressions 7, are laterally engaged by the sides of the cover and prevent its lateral displacement on the 35 base.

The base is pierced by holes 12, 13, 14 and 15 to accommodate the lead wires, while adjacent these apertures are located on the plateaus 11 the combined wire and switch 40 terminals 16, 17, 18 and 19, each having a base 20 and an up-standing lug pierced to receive a binding screw 21. Holes 22 through the base accommodate screws by which it may be secured on any suitable 45 support. I prefer to arrange the binding screw standards in planes substantially radial to the axis of the base, with the binding screws of the terminals coacting with each switch blade, faced toward each other.

50 This arrangement prevents the obstruction of the binding screws by adjacent switches where the latter are mounted in gangs.

As will be noted, each plateau 11 is stepped

to afford an upper level *a* and a lower level *b*. The terminals on the upper levels *a* are provided with contact wings 23 angled upwardly and extending above the plateau. The terminals on the lower levels *b* are angled downwardly toward the depressed area. This arrangement not only makes it 55 possible to use the same blank for all of the terminals, (though the contacts must be offset in opposite directions) but also lessens the amount of metal required for the terminals, since the mounting of the latter on 60 the upper and lower plateau levels lessens the necessary length of the contact lugs while still maintaining their requisite spacing from the switch blades in the open-circuit position of the switch.

70 Each terminal plate 20 is secured to the insulating base 6 by a screw 25 adjacent the wire terminal standard, and by a second screw 26 adjacent the contact flange. These screws not only hold the terminal plate 75 firmly on the insulating base, but are arranged to stand to best advantage the strains put upon the terminal on the one hand by the manipulation of the binding screw 21, and on the other hand by the engagement 80 of the switch blades with the contacts.

The switch mechanism is mounted on a frame struck from sheet metal and angled to shape, and comprises a pair of spaced A-shaped standards 27 and 28 united at their 85 bases by webs 29 and 30. The latter are pierced at 31 to receive the securing screws 32 which pass up through the base 6. The upper ends of the standards are pierced in register at 33 to afford a bearing for the 90 switch operating lever, while lugs 34 are outwardly offset and rounded to form bearing studs on which the switch yoke is pivoted. The simple blank for the switch frame is 95 illustrated in Fig. 5, and the economies resulting from its form will be apparent from the fact that its shape is such that only very little waste results in striking it from a plate or strip of sheet metal. The forming dies are readily made.

100 The switch yoke 35 carries the switch blades 36 and 37 which are insulated therefrom by washers 38. The blades are held in position by the U-shape brackets 39, the flanges 40 of which bear through washer 105 plates, against the insulation 38, while the

legs 41 of the brackets are passed through the parts and are swaged over the outer face of the yoke arms 35 to hold the parts rigidly assembled. The bridge elements of 5 the brackets are to be slotted at 42 to afford open bearings which rest upon the trunnion flanges 34 of the frame. Inasmuch as the yoke straddles the frame and the brackets bear against the outer faces of the standards 10 27 and 28, they serve to prevent the standards from separating under lateral strains on the operating lever in a direction at an angle to its normal plane of oscillation.

The operating lever comprises a tubular 15 section 43 slotted at its inner end to receive a plate-like extension 44 to which it is riveted by depressing at 45 the metal of the legs of the tubular section 43 into suitable apertures in a plate-like member 44, as clearly 20 shown in Fig. 2. The plate-like extension 44 of the lever is arranged between the standards 27 and 28 of the frame and serves as a spacer therefor. It also is provided with laterally extending lugs 46 which take into 25 the bearing apertures 33 at the head of the standards 27 and 28. At its lower end the plate is provided with stop wings 47 engaging the legs of the A-shaped standards 27 and 28, which thus limit the throw of the 30 lever. At the same end of the plate 44 it is notched at 48 to form a bearing for the head 49 of the guide pin 50 for the switch spring 51 compressed between said head and the bridge element of the yoke 35 through a 35 hole 52 in which the end of the guide pin passes. The plate 44 is also pierced at 53 to accommodate the side wings of the head 49 of the spring guide pin in the angular position of the latter.

40 At its outer end the operating lever 43 is tapped to receive a screw 54, by which the operating thumb piece 55 is held in position. The operating lever works in a dome 56 formed in the cover 9, the dome being slotted 45 at 57 to permit of the angular movement of the lever. In order to close this slot against the entry of moisture and dirt to the switch chamber, I associate with the thumb piece 55 a shield 58 shaped to the 50 curvature of the dome 56. The shield is pressed upon the dome by a coil spring 59 surrounding the stem of the screw 54 and engaged between the head of the screw and the bottom of the well 60 formed in the outer 55 end of the thumb piece. The constant pressure of the spring 59 holds the shield 58 in close engagement with the cover and thus not only maintains a practically water-tight joint between these parts, but also serves 60 to maintain the cover firmly upon the insulating base 6. The yielding connection between the thumb piece 55 and the operating lever permits the thumb piece to slide longitudinally on the shank of the screw 54, so that it is not necessary that the dome

56 should have a curvature such that its axis corresponds to the axis of oscillation of the operating lever 43, in order to maintain the shield 58 in close engagement with the dome at all times. This feature is of further advantage in that any shocks to which the thumb piece may be subjected, are not transmitted to the switch mechanism with resultant danger of injury thereto, but are taken up by the cover 9 and heavy insulating base 6. This is a matter of considerable importance when the switch is installed where it is apt to have rough usage—such for instance as upon the runner portion of a vacuum cleaner, where the usual practice 80 is to operate the switch by means of the foot. It will be noted, furthermore, that while the throw of the lever is limited by the impingement of the webs 47 of the plate 44 against the edges of the frame standards 27 and 28, the shield 58 also serves as a stop, bearing against the cover in the opposite extreme positions of the switch lever, and thus affording a direct mechanical engagement 85 between the lever and cover serving to prevent over-strain upon the switch frame and mechanism.

The toggle operation of the switch is well understood in the art and need not be explained in detail.

The construction as a whole is simple, economical and extremely efficient in practice. While modifications in detail of construction will readily occur to those skilled in the art, such departures are not to be regarded as falling outside the scope of what I claim as my invention.

I claim—

1. In an electric switch, a switch operating lever comprising a tubular member slotted at one end, and a plate-like extension of the lever entering said slot and riveted to the legs of the tubular member, said plate-like extension of the lever having at its free end a lateral projection adapted to serve as a stop to limit the throw of the lever.

2. In an electric switch, a switch frame having spaced standards, a switch lever arranged between said standards and comprising a tubular member slotted at one end, a plate-like extension of the lever entering said slot and secured to the legs of the tubular member, laterally projecting lugs on said plate-like member forming bearing studs journaled in the frame standards, and a lateral stop projection on the free end of the plate cooperating with the frame to limit the throw of the lever.

3. In an electric switch, an oscillating switch operating lever tapped at one end, a thumb piece arranged at said end, a screw passing through said thumb piece to secure the same to the lever, and a spring interposed between said screw and thumb piece to permit longitudinal play of said thumb piece.

with respect to the lever, in combination with a switch cover apertured to permit the oscillation of the lever, and against which said thumb piece constantly bears through the action of said spring.

4. In an electric switch, an oscillating switch operating lever tapped at one end, a thumb piece arranged at said end, a screw passing through said thumb piece to secure the same to the lever, and a spring interposed between said screw and thumb piece to permit longitudinal play of said thumb piece with respect to the lever, in combination with a switch cover apertured to permit the oscillation of the lever, said thumb piece having an associated shield overlying the slot in the cover in all positions of the switch lever.
5. In an electric switch, an oscillating switch operating lever tapped at one end, a thumb piece arranged at said end, a screw passing through said thumb piece to secure the same to the lever, and a spring interposed between said screw and thumb piece to permit longitudinal play of said thumb piece with respect to the lever, in combination with a switch cover having a slotted curved portion through which the lever operates, said thumb piece having an associated shield shaped to the curvature of the cover and overlying the slot in all positions of the

lever, said spring serving to constantly press said shield against the cover.

6. In an electric switch, a switch operating lever pivoted for oscillation, and comprising a tubular member slotted at one end to receive a plate-like extension and tapped at its opposite end, a thumb piece arranged at the latter end of the lever, a screw passing freely therethrough and taking into the tapped end of the operating lever, a spring engaged between the head of the screw and the thumb piece, and a switch cover curved and apertured at the curve to accommodate and permit oscillation of said lever element, said thumb piece being constantly pressed upon said cover by the action of said spring.

7. In an electric switch, an insulating base, a switch mechanism mounted thereon and having an oscillating switch operating lever, a slotted cover for enclosing said mechanism, and a thumb piece for said oscillating lever, said thumb piece overlying the cover, and a spring connection between said thumb piece and lever serving to constantly press the thumb piece against the cover to maintain the latter seated on the base.

In testimony whereof I have signed my name to this specification.

ARVID H. NERO.
